NUMBER DISPLAY ARRANGEMENT

George Thomas Baker, Liverpool, England, assignor to Automatic Telephone & Electric Company Limited, Liverpool, England, a British company

Application May 23, 1947, Serial No. 750,142
In Great Britain June 12, 1946

9 Claims. (Cl. 177—337)

1

The present invention relates to display arrangements and is more particularly concerned with arrangements adapted to display variable items of information.

Display devices of this type find many applications in the signalling art and the design of display devices suitable for the various applications has been a problem on which considerable time has been spent without attaining a completely satisfactory solution. One particular application is to number display systems used in automatic telephone systems. One form of display at present in use consists of a bank of lamps arranged behind a stencil plate, the lamps being divided into, for example, four groups of ten lamps to provide a four-digit display. The stencil plate has $\frac{1}{4}$ " characters so that the whole display occupies a width of approximately 15 inches. This display is not entirely satisfactory since the exaggerated spread together with the variable horizontal and vertical displacement renders the numbers comparatively difficult to read. Another type of display such as used with totalisators employs a so-called monogrammic indicator in which the characters are built up from small elements but this is entirely unsuited for a small display. In addition there are numerous mechanical solutions to the problem using, for instance, number wheels, dial pointers and so on but their chief drawback is the slowness of setting and further they are often difficult to read, extravagant in space and are complicated in construction.

It is one of the objects of the present invention to provide an arrangement which is compact and which provides a clear display of one or more of a plurality of predetermined characters in any desired relationship.

According to one feature of the invention in an arrangement for displaying one or more characters on the screen of a cathode ray tube, the movement of the spot is controlled by a combination of varying character-producing potentials and steady spacing or layout potentials.

According to a further feature of the invention in an arrangement for displaying a plurality of characters on the screen of a cathode ray tube, varying potentials are used to trace the outline of each of said characters and steady potentials of appropriate value are used to locate each of the characters at any desired position on the screen. Preferably electrostatic deflecting means are employed for controlling the movement of the spot and the alternating potentials are applied to the deflection plates. It will however be under-

2

stood that electromagnetic deflection may be used in which case the alternating potentials will be converted into alternating currents for application to the deflecting coils.

5 According to another feature of the invention in an arrangement for causing the sustained display of a plurality of characters on the screen of a cathode ray tube, periodically varying potentials are used to cause the spot to traverse the outline of a character at a speed of repetition sufficient to cause the appearance of a sustained display and steady potentials of appropriate value are used to locate each of the characters at any desired position on the screen.

10 According to a further feature of the invention in an arrangement for displaying a plurality of characters on the screen of a cathode ray tube by successively applying to the tube a series of combinations of potentials, each combination consisting of periodically varying potentials to produce the appropriate character and direct potentials to provide the correct spatial relationship between successive characters. Preferably each individual character will be repeated at high speed while the complete trace will also be repeated rapidly as long as the particular display is required. Persistence of vision will cause the appearance of a steady display and it will be appreciated that the display will be improved by the use of a cathode ray tube having an appreciable after-glow.

15 According to a further feature of the invention in an arrangement for displaying any one or more of a plurality of predetermined characters on the screen of a cathode ray tube, predetermined characters are adapted to be displayed by means of a generator arranged to produce periodically varying potentials suitable for tracing the outline of each of said characters, selection of one or more of the potentials being controlled by external means to cause one or more selected characters to be displayed on the screen.

20 According to a further feature of the invention in an arrangement for displaying one or more of a plurality of predetermined characters on the screen of a cathode ray tube comprises means for generating periodically varying potentials suitable for producing a plurality of predetermined characters, means for selecting one or more of said alternating potentials as determined by the required characters and means for rendering effective said alternating potentials to produce the desired display.

25 According to a further feature of the invention an arrangement for displaying any one or

more of a plurality of predetermined characters on the screen of a cathode ray tube includes means for generating potentials suitable for causing the spot to trace each of said characters.

According to a further feature of the invention in an arrangement for generating control potentials suitable for causing any one or more of a plurality of predetermined characters to be displayed on the screen of a cathode ray tube, an alternating potential is applied to a plurality of impedances arranged to vary periodically in time to generate potentials suitable for producing said characters.

The invention has particular application to telephone systems in which information relating to a connection, for instance, the number of a calling and/or called subscriber or the duration of the call and so on, is transmitted to a central point where it is rendered available by a record or display.

According therefore to a further feature of the invention, in a telephone system provided with equipment for rendering available information relating to a connection, the equipment includes a cathode ray tube for causing the display of individual characters on the screen, the selection of a plurality of characters to display the desired information being effected in accordance with impulses transmitted to the equipment.

These and other features of the invention will be better understood from the following description of one method of carrying it into effect, reference being had to the accompanying drawings comprising Figs. 1 to 8. In the drawings:

Fig. 1 shows the layout of the main components.
Fig. 2 shows the circuit of the varying voltage or figure generator.

Fig. 3 shows the method of analysing a character.

Fig. 4 shows a scale employed in determining the shape of the rotating vanes.

Fig. 5 shows typical shapes of the vanes and Figs. 6 and 7 show two constructional views of the variable voltage generator.

Fig. 8 shows, in circuit diagram form, the schematic layout of the system, along the lines of Fig. 1, but more in detail.

Referring first to Fig. 1, the equipment comprises four main components, first the cathode ray tube CRO which may be any of the standard units, preferably of the slow screen type, of a size determined by the display requirements. The second component is the layout control circuit LC which feeds the tube successively with the appropriate varying voltages or figure voltages over the leads OF to make up the display and superimposes the necessary steady potentials over the leads LP to locate each figure in the appropriate position in the frame or on the screen.

This equipment may consist of a uniselector as shown in the drawing together with a number of resistors and in many cases equipment already provided to serve other purposes may be used. The uniselector is shown as having two wipers, one for successively feeding the fixed or locating potentials and the other for successively feeding the X- and Y-varying voltages to the cathode ray tube. It will, of course, be understood that the drawing is purely diagrammatic and, in actual practice, the X- and Y-voltages would be fed over separate wipers of the uniselector as shown in Fig. 8.

The third component consists of the figure selector FS which, in actual practice would form part of the apparatus controlling the display.

Again this equipment may consist of a plurality of uniselectors as shown in Fig. 1 or 8 each of which feeds the appropriate X- and Y-voltages to the contact banks of the uniselector in the layout control circuit. If, for example, four characters are to be displayed, provision would have to be made for feeding four sets of X- and Y-voltages and four uniselectors would be necessary. These uniselectors would be set by means external to the equipment, for instance, by impulses transmitted thereto, the leads from the figure generator being multiplied over the appropriate banks of the uniselectors. The arrangement shown in Fig. 1 is purely diagrammatic in that each uniselector is shown as feeding both X- and Y-voltages to the layout control circuit. Alternatively the figure selectors may consist of groups of relays which selectively connect the contacts of the layout selector to appropriate terminals of the figure generator.

Finally the fourth component consists of the figure generator FG which provides the alternating potentials for producing the trace corresponding to the integers, 1 to 0. One such unit will supply a large number of tubes and thus the system is particularly suited to providing a multiplicity of adjacent but otherwise independent displays.

The circuit of the figure generator is shown in Fig. 2. The oscillator functions at about 500 kc., and feeds the common rotor of the multi-unit variable condenser shown as C2X, C2Y, C3X, C3Y and so on. Each fixed plate is connected through a load resistance RA2X, RA2Y, RA3X, RA3Y and so on to earth. The high frequency potential developed across the resistance, is rectified by the appropriate one of the dry-plate rectifiers MR2X, MR2Y, MR3X and MR3Y. The smoothing units RB2X and CA2X and so on are introduced to prevent the high-frequency blurring the output, which is normally situated in the lower audio frequency band.

Each figure with the exception of "1" requires two control potentials and there are thus nineteen plates and output terminals. The actual construction of the figure generator is shown in Fig. 6 from which it will be seen to consist of a pressed steel base 10 provided with bearing brackets 11 and 12 which are secured to the base 10 by screws 13 and 14. The base 10 also carries a motor 15, secured to the base by screws 16, an oscillator 17 shown in dotted outline and the various resistors and rectifiers 18 associated with the fixed capacitor blades and the capacitors 19 forming part of the smoothing circuits. The motor 15 serves to drive the shaft 20 which by means of the insulating coupling 21 is connected with the shaft 22. The shaft 22 is mounted in the brackets 11 and 12 by means of ball races 23 the latter being a push fit in phenol fibre insulating plates 24 suitably secured to the brackets by screws 32. The shaft 22 carries the condenser vanes 1Y to 8Y, corresponding pairs of which e. g. 2X and 2Y, are primed to metallic bushes 25 secured to the shaft 22 by retaining screws 26. Intermediate metallic bushes 27 serve to separate each pair of vanes from adjacent pairs. The rotating condenser vanes co-operate with one pair of fixed plates or blades 28 each pair being spaced apart by metallic distance pieces 29 and secured to insulating blocks 30 by screws 31. It will be noted that in Fig. 7, which is an end view of Fig. 6 from the top of the figure, the rotatable vanes are shown as circular. This is merely for the convenience of drawing since the

irregular shape of the vanes used in practice is difficult to show on a drawing of this nature. Electrical connections may be made to the vane shaft 22 by means of a brush and slip ring arrangement (not shown) or by a spring-loaded ball engaging with the end of the shaft.

It will be understood that as the motor is continuously operating and the output from the oscillator is applied to all the rotating vanes, the nineteen variable voltages are always available across the various load resistances. The desired varying voltages will be taken from the load resistances according to the setting of the figure selector and will be applied in succession to the cathode ray tube by the rotation of the wipers of the layout control uniselector. The time during which the wipers of the latter uniselector remain on a bank contact is greater than the time of rotation of the vane shaft 22 so that each character may be traced a number of times before passing on to the next. If the number of characters to be displayed is predetermined for example, four, the first four contacts of the layout control uniselector may be multiplied through the bank and the complete trace will be continuously repeated as long as the uniselector continues to step. In some cases it may be sufficient to trace each character once, the determining factor being the afterglow characteristics of the screen.

It will be seen that the output potential of the figure generator depends on the instantaneous capacity of the rotating condenser and if the vanes are correctly shaped almost any desired output can be achieved. The general principles for shaping the vanes will now be described.

Consider the reproduction of an outline, as for example, the "2" shown in Fig. 3. Imaginary axes can be drawn through the resting position of the spot, one parallel to the deflection produced by the X plates the other parallel to the Y plate deflection. On a cathode ray tube the deflections are substantially proportional to the applied potentials, so that the distances from these axes i. e. the x and y co-ordinates represent the required deflection potentials. The outline shown is therefore a relationship between x and y of the form,

$$x=f(y) \quad (1)$$

This curve is traced out by the movement of the spot and therefore the relationship is more accurately expressed in terms of a parameter t ,

$$x=f_1(t) \quad (2)$$

$$y=f_2(t) \quad (3)$$

The traverse is repeated many times hence these represent periodic functions. The load resistance (RA2X and so on, Fig. 2) is kept relatively small and the output potentials are therefore roughly proportional to the instantaneous capacity of the variable condensers. Therefore Equations 2 and 3 can be written

$$Cx=f_1(t) \quad (4)$$

$$Cy=f_2(t) \quad (5)$$

where Cx , Cy are the capacities of the x and y condensers respectively.

The outline should have an even illumination and, therefore, the spot must move at a constant velocity along the trace. The curve is therefore divided into a number of equal divisions, each of which represents a time unit. In practice, it has been found more convenient to divide each figure into its salient features and to make each feature

an integral number of time units while preserving the overall equality as near as possible. This makes it easier to reproduce those features which are repeated in two or more figures. Thus in "2" the base line is allowed three and the remainder of the curve seven out of the ten divisions into which the trace is divided.

The rotor has a substantially constant angular velocity and the time divisions also represent angular position of the shaft. Equations 4 and 5 then become

$$Cx=f_1(\theta) \quad (6)$$

$$Cy=f_2(\theta) \quad (7)$$

Thus giving the capacity required from the x and y capacitors for any position of the shaft. These two polar curves can be obtained directly from Fig. 3 and, if the fixed blades were of negligible width, they would represent the desired rotor shape.

In practice, it is necessary to make the fixed plates as wide as possible and an 18 deg. segment has been found convenient. Before Equations 6 and 7 can represent overlapping areas of the capacitor vanes, two corrections are necessary.

Firstly due to the wedge shape of the fixed vanes the radial scale must be adjusted so that the divisions on the scale represent equal increments of overlapping area. Referring to Fig. 4 this is effected by first selecting suitable radii R_0 and R_{10} for the circles B_0 and B_{10} when the radius of the circle B_1 is given by

$$R_1^2 = R_0^2 + \frac{1}{10}(R_{10}^2 - R_0^2)$$

The remaining radii are similarly determined. The radius units are thus made proportional to the square of the distance from the origin.

Secondly, the perimeter of the rotating vane does not cut the fixed blades in an arc of a circle, but in general, includes varying heights. The actual area is represented by an integral taken between two radii, 18 deg. apart. Fortunately the sine functions and straight lines which compose the main part of the figures integrate into sine functions and straight lines respectively, and therefore this effect does not entail a great deal of modification, except at discontinuities. One or more of these occur in most figures and the reversals at either end of the traverse provides further examples. A theoretically perfect solution cannot be obtained, but the shape of the figures are not critical and approximations can be obtained, which give a divergence from the ideal almost unnoticeable on the trace.

It has been found that once the salient features of the various figure shapes have been studied, a great deal of latitude exists in the plate shape while still preserving a reasonably symmetrical figure; this latitude can be used to make the plates easier to cut. The complete procedure is as follows. Draw the required outline on a Cartesian frame as shown in Fig. 3. Divide the trace or each salient feature thereof into a convenient number of equal divisions, and make a polar plot on the scale shown in Fig. 4, where the semi-circle is divided up into as many segments as there are trace divisions, (the remainder of the circle is used for the reverse traverse). Correct for discontinuities by approximate means and generally smooth the final result to give a smooth rounded figure. Typical outlines achieved by the above methods are shown in Fig. 5.

A further correction can be introduced to allow for the fact that the value of the load re-

sistance is not negligible, since electrical efficiency requires this to be fairly high in comparison with the capacitor impedance. The effect, however, is to give a slight flattening at the upper end of the figure and it is fairly simple to allow for this when drawing the original outline.

The required outlines should be drawn several times fullsize. They can then be clipped onto a phenol-fibre board and the outline carefully pricked through to the board. When the paper is removed the marks may be joined up with a scribe into a smooth continuous groove, which can be used as a master on a pantograph engraving machine to inscribe the profile at the correct size upon a steel sheet. When this is cut out and case-hardened, it may be used as a template to produce any number of the required vanes which are formed in aluminum or similar metal or alloy.

It will be seen that the invention provides an extremely compact and flexible form of display arrangement and while the description of the preferred embodiment refers to the display of figures, it will be understood that other characters may be displayed either alone or in combination with figures. It will also be understood that arrangements other than those described above may be employed for applying the variable and steady voltages to the cathode ray tube.

The applications of the display arrangement are many and will be obvious to those skilled in the signalling art. Reference has already been made to its application to automatic telephone systems either for displaying a called number or for displaying a calling number in systems employing line identification equipment. The impulses or other signals representing such numbers would be transmitted to the equipment and would control, preferably directly, the switching mechanism of the figure selector. In telephone systems employing equipment for automatically determining particulars of connections, the arrangement of the present invention may be employed in place of a recorder or printer by providing equipment for photographing each display, so that a permanent record is obtained of each display which in this case will consist of the particulars of a connection. It will be understood that other methods of controlling the figure selector than that shown diagrammatically in Fig. 8 are possible, and that under certain conditions all of the FS uniselectors could be set simultaneously from markings, rather than successively, from dialled impulses.

I claim:

1. In a character outline display system utilizing a cathode ray tube, a generator for producing a steady alternating voltage wave of a single frequency, a plurality of variable impedances connected to said generator each having a rotatable element, said rotatable elements all having different configurations corresponding respectively to the outlines of the different characters available for display, means for simultaneously rotating said rotatable elements to cause said impedances to convert said steady alternating voltage into a plurality of varying voltages corresponding respectively to said different character outlines, remote control means for selecting certain of said varying voltages, and automatic means for successively and repeatedly applying said selected voltages to said tube to cause the outlines of the corresponding characters to be traced and to be displayed side by side simultaneously by said tube.

2. In a character outline display system in-

cluding a cathode ray tube, a cyclically operating generator for producing a uniform alternative voltage wave, a plurality of variable condensers connected to said generator each having a rotatable plate and a fixed plate, all of said rotatable plates provided respectively with different configurations corresponding to the outlines of the different characters to be used, a shaft for repeatedly rotating said rotatable plates to cause said rotatable and fixed plates to convert said uniform alternating voltage into a plurality of varying alternating voltages corresponding respectively to said plate configurations, means for converting said varying alternating voltages to correspondingly varying unidirectional voltages, remote control means for selecting one or more of said varying unidirectional voltages at will, and cyclically operating means for successively impressing said selected voltages on said tube at regularly repeated intervals to cause said tube to display the outlines of the corresponding characters simultaneously in laterally spaced apart relationship.

3. A display system as in claim 2, in which the configurations of said rotatable plates are such as to cause said tube to trace the outline of each of the displayed characters first in one direction and then in the other, as long as the corresponding varying unidirectional voltages are impressed on said tube.

4. A display system as in claim 2, in which the configurations of each of said rotatable plates are such as to cause said tube to trace the outline of each of the displayed characters once in each direction for each rotation of said shaft during the times the corresponding varying voltages produced from such plate are connected to said tube.

5. A display system as in claim 2, in which two condensers are normally employed for each of said different characters, to separately and simultaneously control the abscissa and ordinate values with respect to common base lines for each of said character outlines containing such values.

6. In a display system for displaying a plurality of characters simultaneously in outline on the screen of an oscilloscope, a generator common to said system for producing a steady alternating current of a single frequency, a plurality of variable condensers connected to said generator, a metallic plate for each said condenser each having a different peripheral configuration corresponding respectively to the abscissa and ordinate outlines of each one of the different character outlines utilized in the system, said respective outlines traced alternately in opposite directions on each plate, means for rotating said plates in unison to cause said condensers to change said steady alternating current into a plurality of varying alternating currents corresponding to said peripheral configurations, means for automatically translating said varying alternating currents into correspondingly varying unidirectional potentials, a first switching means for directly selecting a plurality of said last varying potentials, and a second switching means cyclically operated for successively applying said selected potentials to said oscilloscope to cause the corresponding character outlines to be displayed simultaneously on said screen.

7. In a display system as in claim 6, a plurality of steady unidirectional potentials of different magnitudes and corresponding in number to the maximum number of characters to be displayed on said screen at one time, and plural

channels in said second switching means for applying one of said plurality of steady potentials to said oscillograph with each of said selected varying potentials to cause said displayed character outlines to be maintained in a definite spaced relationship with one another on said screen.

8. In a number display system for displaying plural digit numbers on the screen of a cathode ray tube, a generator common to said system for producing a uniform alternating voltage, a group of impedances connected to said generator, a metallic plate for each said impedance each having a different peripheral configuration corresponding respectively to the instantaneous abscissa and ordinate values constituting the outlines of the various numeral characters employed, means for rotating said plates in unison to cause said impedances to convert said uniform alternating voltage into a plurality of varying alternating voltages corresponding to said peripheral configurations, rectifier means for converting said varying alternating voltages into correspondingly varying unidirectional voltages, a plurality of steady unidirectional layout voltages of different magnitudes, a first switching means directly operable to select one or more of said varying unidirectional voltages, and a second switching means automatically operable to successively and repeatedly apply said selected

varying voltages and said layout voltages to said tube to cause said tube to display the number corresponding to said selected varying potentials by tracing the outlines of the selected characters successively in opposite directions side by side on said screen.

9. A number display system as in claim 8, in which said first switching means comprises a plurality of multi-contact stepping switches individually settable in response to received impulses, and in which said second switching means comprises a unidirectional stepping switch having three contact levels, with said plurality of switches connected respectively to successive contacts in two of said levels, and said layout potentials connected respectively to corresponding successive contacts in the other of said levels.
